DIE CASTING MACHINE

William J. During, Syracuse, N. Y., assignor to
Precision Castings Company, Inc., Syracuse,
N. Y., a corporation of New York

Application February 15, 1930. Serial No. 428,681

7 Claims. (Cl. 22—92)

This invention relates to certain new and useful improvements in die casting machines.

It has been found by experience to be very dangerous to operate a die casting machine which is constructed to be actuated pneumatically due to the elasticity of air and the expansion thereof being uncontrollable after the air, under pressure, has been released. Serious accidents have many times occurred in the operation of such a machine after the air, under high pressure, has been released to discharge the molten metal from the die pot due to various reasons as, for instance, when the discharge nozzle for the delivery pot is improperly seated or when cores have been unintentionally omitted from the die or mold, or in other cases, where the die was not entirely closed or securely maintained in the closed position.

The main objects of this invention, therefore, are the production of a die casting machine of strong and durable construction which may be quickly, easily and positively operated with a maximum degree of safety for producing castings.

In carrying out the above mentioned objects, I have provided a structure whereby the die or mold are moved to and from the discharge nozzle of the delivery pot and to and from each other at certain related times and positions of movement by hydraulically operated means which is controlled by the manipulation of a single control valve thereby providing a reliable means for positively seating the delivery nozzle and closing the dies which works in conjunction with a lock mechanism for positively maintaining said dies in the closed position during the charging operation.

Another feature of this invention is a simply constructed hydraulically actuated mechanism for forcing the molten metal from the delivery pot into the die or mold. This mechanism provides a maximum degree of safety in the operation of the machine in that the flow of the molten metal may be controlled substantially instantaneously which is not true of any pneumatically actuated metal discharge mechanism due to the impossibility of controlling the expansion of compressed air after the air is released.

Still another advantage of this invention is that a direct application of much higher pressure is permitted and at a much lower cost than when the mechanism is actuated by pneumatic principles.

Other objects and advantages relating to the details of the structure and form and relation of the parts thereof will more fully appear from the following description taken in connection with the accompanying drawings in which:

Figure 1 is a side elevation of a machine embodying the various features of this invention.

Figure 2 is an enlarged detail vertical section

of the device as disclosed in Figure 1 with a greater portion of the furnace and delivery pot removed.

Figure 3 is a detail horizontal section, taken in the plane of the line 3—3, Figure 2, illustrating the action of the toggle link connection between the die supporting carriage and die supporting plate.

Figure 4 is a detail vertical transverse section taken in the plane of the line 4—4, Figure 3.

Figure 5 is a detail vertical transverse section taken in the plane of the line 5—5, Figure 2.

Figure 6 is an enlarged vertical section of the toggle actuating piston and cylinder therefor, taken in the plane of the line 6—6, Figure 3.

Figure 7 is an enlarged longitudinal vertical sectional view of the piston and cylinder for actuating the die carriage.

Figure 8 is a vertical longitudinal section of the control valve for the die carriage taken in the plane of the line 8—8, Figure 1.

Figure 9 is a detail vertical transverse section of the delivery pot taken on line 9—9, Figure 1.

Figure 10 is a detail vertical longitudinal section of the delivery pot taken in the plane of the line 10—10, Figure 9.

Figure 11 is a detail plan view partly in section, of one of the oil feed lines connecting the carriage operating cylinder with the die operating cylinder, taken substantially on line 11—11, Figure 1.

The machine, as illustrated in the drawings, consists of a frame —1— and a furnace —2—. The furnace —2—, in this instance, is of substantially rectangular form and supported upon two pairs of legs or feet —3— and —4— positioned at respective corners of the furnace —2—.

One pair of the furnace legs —4— positioned adjacent the main frame —1— is adapted to support one end of the frame —1— and is rigidly secured thereto by bolts —5—. The other end of the main frame —1— is supported by a pair of legs —6— provided one at each corner of the rear end of said frame.

The frame —1—, in this instance, is substantially rectangular in plan view and consists of a pair of parallel spaced longitudinal side rails —7— connected at one end with the respective leg —6—, said side rails being connected by transversely extending end rails —8— and —9— and cross rails —10— and —11— positioned in spaced relation intermediate the end rails —8— and —9—.

A die supporting carriage —12— is slidably mounted for longitudinal reciprocative movement upon the upper face of the frame —1—. The carriage —12—, in this instance, is composed of a horizontally disposed slide member —13—, a vertically disposed fixed die supporting

plate —14— and a vertically disposed cylinder supporting plate —15—.

The slide member —13— extends substantially the entire length of the frame —1— from the rear end thereof to within a short distance of the forward end and is slidably mounted upon the upper face of inwardly projecting flanges —18— provided near the upper edge of the side rails —7—. Said flanges extend longitudinally 10 of the rails from front to rear with the upper face thereof positioned below the upper edge of the respective side rail —7— thus forming upwardly extending flanges —17— extending longitudinally of the frame —1—, with one positioned at either side of the slide —13— for maintaining said slide against lateral movement.

The slide —13— is maintained in sliding contact with the upper face of the supporting flanges —16— by two pairs of guide plates —18— and —19— positioned in parallel spaced relation one pair at either side of the frame —1— over the guide flanges —17— and the adjacent outer edge of the slide —13—. Each guide plate —18— and —19— is secured in spaced relation to the upper edge of the respective flange —17— by means of screws or bolts —20—. The upper face of the slide member —13— is provided with a centrally located guideway —21— which extends substantially the entire length of the slide —13—, said guide being formed by parallel, longitudinal and upwardly extending flanges —22—, positioned to slide inside the respective guide plates —18— and —19— and having their inner opposed faces —23— inclined downwardly and outwardly.

The rearwardly positioned cylinder supporting plate —15— is substantially rectangular in face view with the lower edge thereof provided with a downwardly extending flange or projection —24— which extends transversely of the slide —13— with the outer edges thereof inclined outwardly to form beveled edges —25— similar to the inclined faces —23— of the guideway —21— and adapted to fit beneath said inclined edges for slidably maintaining said plate in operative position upon the slide —13—.

The plate —15— is provided with a plurality of, in this instance, four holes or openings —26— extending therethrough and positioned one near each outer corner of the plate for receiving one end of a respective tie rod —27— or —28—. The upper positioned tie rods —27— extend forwardly of the plate —15— and have their forward ends —27'— slightly reduced in diameter and positioned in respective holes or openings —14— provided in the upper portion of the fixed die plate —14— near the outer edge thereof in alignment with a respective opening —26— in the upper portion of the cylinder supporting plate —15—.

The forward ends of the tie rods —27— are secured to the die plate —14— by means of nuts —29— screw threaded on the outer ends of said tie rods, the plate —14— being secured by screws or bolts —30— to the forward end of the slide member —13— to move therewith.

The cylinder plate —15— is adjustably secured to the rear portion of the rods —27— by means of nuts —31— screw threaded on the rear ends 70 of the respective rods and positioned one at either side of the plate —15—. The lower positioned rods —28— extend through a respective lower opening —26— in the plate —15— to a position intermediate said plate and the fixed plate —14— 75 with the forward ends thereof secured in respec-

tive brackets —32— secured to the upper face of the slide member —13— by screws —33— and dowel pins —34—.

The brackets —32— are positioned one adjacent either longitudinal side of the slide —13— and extend outwardly therefrom through the space formed between the adjacent spaced ends of respective guide plates —18— and —19— so as to be in registering alignment with a respective opening —26— provided in the lower portion of the plate —15—.

The rods —28— are adjustably secured to the plate —15— similarly to the manner in which the upper positioned rods —27— are secured to the plate; that is, by nuts as —35— positioned one on either side of the plate so that by manipulating the nuts —31— and —35—, the plate —15— may be adjusted along the slide —13— to or from the fixed die supporting plate —14— for varying the distance between said plates to accommodate die sections as —36— and —37—, of different widths which may be carried by the fixed plate —14— and a movable die supporting plate —38— co-acting with the fixed die supporting plate —14—.

The movable die supporting plate —38— is 100 slidably mounted upon the slide member —13— in the guideway —21— intermediate the fixed die supporting plate —14— and the cylinder supporting plate —15—.

The movable plate —38— is L-shaped in longitudinal cross section with one leg —39— thereof disposed in a vertical plane at substantially right angles to a horizontally disposed leg —40—. The vertical leg —39— is substantially rectangular in face view for supporting one of the die sections 110 as —37— upon the front face thereof. The horizontally disposed leg —40— extends rearwardly from the vertical leg —39— and is provided on its lower surface with a pair of spaced downwardly extending flanges —41— extending longitudinally of the leg along the outer edges thereof and having their outer edges slanting downwardly and outwardly to form a beveled face —42— similar to the faces —23— of the flange members —22— and adapted to travel beneath said beveled faces —23— for guiding the movable die supporting plate —38— for longitudinal reciprocal movement on the slide member —13—.

The upper surface of the leg —40— is provided with a centrally located guide channel 125 —43— extending longitudinally of the leg —40— from the rear end thereof to within a short distance of the vertical leg —39—.

A rack member —44— is slidably mounted in said guide channel —43—, has its opposite vertical edges provided with gear teeth adapted to engage the teeth of respective segments —45— secured to or made integral with a link member —45— to swing therewith, said links having one end thereof pivotally connected at —46— to respective forwardly projecting lugs —47— provided on the front face of the cylinder supporting plate —15—.

An intermediate lever —48— has one end thereof pivotally connected at —49— to the other end of the link —45— and the other end of the lever —49— is pivotally connected at —50— to the rearward end of a link —51— which, in turn, is pivotally connected at —52— to respective rearwardly extending lugs —53— secured to or 145 made integral with the rear face of the vertical leg —39— of the movable die supporting plate —38—.

A cross head —54— disposed in a horizontal plane over the rack member —44— intermediate 150

the cylinder supporting plate —15—, and the front vertical leg —39— of the movable die supporting plate —38— has the outer ends thereof pivotally connected at —55— to a respective lever 5 —48— intermediate the ends thereof to form a movable pivotal support for said levers about which the levers rotate during the action of the levers —48— and links —45— and —51—. The cross head is guided for longitudinal rectilinear 10 movement during the action of said arms and levers by a centrally located downwardly extending rib or tongue —56— provided on the under-surface of the cross head —54— and adapted to travel in a groove —57— provided in the forward 15 end of the upper surface of the rack —44—.

The lugs —53— provided on the movable die supporting plate —38— and also the lugs —47— connected with the cylinder supporting plate —15—, are positioned in spaced relation at equal 20 distances either side of the rack —44—, and the levers —48— and links —51— are provided with projections —58— and —59— respectively which, when the levers and links are in the extended position as illustrated by dotted lines in Figure 3, 25 abut against each other and prevent the link and lever construction from passing beyond the dead center.

In other words, the links —45— and —51—, the levers —48— and the cross head —54— constitute a toggle link connection between the stationary cylinder supporting plate —15— and the movable die supporting plate —38— for moving the plate —38— and the die section as —37—, carried thereby into and out of casting relation 30 with the fixed die section —36— carried by the die plate —14— and the pivots —46—, —49—, —50— and —52— for the respective links and levers will be on a straight line when the die sections are in the closed or casting position, and 35 thereby lock the die sections in this position and prevent any possibility of the die opening, due to the backward movement of the die supporting plate —38— when the metal is forced into said die.

During the action of the links —45— and —51— 40 and the levers —48—, it is evident that the cross head —54— will be moved longitudinally between the plate —15— and the movable die supporting plate —38—, but to a less degree than said plate —38—, as illustrated by full and dotted 45 lines in Figure 3. This relative movement of the cross head —54— and the movable die supporting plate —38— is utilized for ejecting the casting formed in the movable die section —37— during the backward or opening movement thereof 50 which is accomplished in the following manner:

Ejector rod —60— has one end thereof positioned in an opening provided in the forward portion of the cross head —54— and adjustably secured thereto by means of a pair of nuts —61— 55 screw threaded on the rod —60— and positioned one at either side of the forward portion of the cross head —54—. The rod —60— extends forwardly from said cross head through suitable registering openings provided in the vertical leg —39— of the plate —38— and an aperture die supporting member —62— secured to the front face of the leg —39—. An ejector plate as —63— is secured to the front end of the rod —60— and has secured thereto a suitable number, in this 60 instance, four ejector pins —64— and —64'— positioned in suitable apertures in the die section —37—, which, when the die section —37— is in the forward position in casting relation with the die section —36—, have their outer ends registering 65 with a casting face of the mold cavity in said die

to form a part thereof, and when the die section —37— is moved to the open position, the ejector pins —64— and —64'— will extend beyond the casting face of the mold cavity due to the different degree of longitudinal movements of the die supporting plate —38— and the cross head —54—, and thereby eject a casting carried by said die.

The rack —44— and the toggle link mechanism, in this instance, are actuated to move the die section —37— into and out of casting relation with the die section —36— by a piston —65— reciprocally mounted in a cylinder —66— and connected thereto by a suitable connecting rod —67— secured at one end to the piston —65— and connected at its forward end to the rear end of the rack member —44—.

An upwardly projecting lug —68— is provided on the upper surface of the rear end of the rack —44— and is provided with an aperture therethrough for receiving the rod —67— which is adjustably clamped to the lug and, therefore, the rack —44— by means of nuts —69— screw threaded on the end of the rod —67— and positioned one at either side of the lug —68—.

The cylinder —66—, in this instance, is a substantially tubular member having one end positioned adjacent the rear face of a rearwardly extending bracket —70— secured to or made integral with the cylinder supporting plate —15—.

A suitable cylinder head —71— is positioned adjacent the other end of the cylinder, said cylinder head —71— and the cylinder —66— being securely clamped to the bracket —70— by means of a plurality of, in this instance, four rods —72— secured at one end in substantially equal spaced relation to the bracket —70— and having their rear ends passing through suitable holes in the head —71— with nuts as —73— screw threaded on the ends of the respective rods 110 for holding the cylinder —66— and head —71— in their operative relation on the bracket —70—.

The piston —65— may be hydraulically actuated in the cylinder —66— by any suitable material, as oil under pressure, which may enter the cylinder through suitable conduits —74— and —75—, and inlet ports —76— and —77—, with which the respective conduits —74— and —75— are connected, said ports —76— and —77— being located one at either end of the cylinder 125 —66— and in communication with the interior of the cylinder a short distance from the respective outer end thereof.

The ports —76— and —77— are also connected with respective ends of the interior of the cylinder —66— by means of by-passes —78— and —79— respectively, the by-pass —78— being positioned in the cylinder head —71— with one end thereof in communication with the interior of the cylinder —66— and connected by a 130 passageway —80— with the part —76— intermediate the ends thereof.

The by-pass —79— is located in the rear end wall of the bracket —70— with one end thereof in communication with the interior of the cylinder —66— and connected by a passageway —81— with the port —77— intermediate the ends thereof. Each of the passageways —80— and —81— has an enlarged portion —80'— and —81'— respectively intermediate the ends 145 thereof, in which is positioned a valve member —82—. Said valve members —82— are of slightly less length than the respective passage —80'— or —81'— and slidably mounted therein for longitudinal movement. The valve members 150

—82— are tubular in cross section with the inner ends thereof closed and tapered to conform to a valve seat —83— and —84— formed of the inner ends of the said portions —80'— and —81'— respectively.

10 A series of apertures —85— are provided in the closed ends of each of the valve members —82— which connect the interior of the valves with the exterior of the beveled ends so that any liquid entering the respective port —76— or —77— may force the respective valve member —82— outwardly away from its seat and then enter through the apertures —85— to the interior of the valve, and thence through the 15 respective passageway —80— or —81— and bypass —78— or —79— to the respective end of the cylinder —66—.

20 A relatively small aperture —86— is also provided in the central portion of the end of the valves —82— for permitting a small quantity of liquid to escape outwardly from the respective by-pass —78— or —79— into the ports —76— or —77— when the valves —82— are in the closed 25 position for retarding or cushioning the movement of the piston —85— as it approaches either end of the cylinder —66—.

30 The fixed die supporting plate —14— has a gate member —87— positioned therein which is in alignment with an inlet port —88— provided in the die section —36—, said gate member being adapted to be engaged by a suitable discharge nozzle —89— provided in the outer end of a spout —170— formed on the upper rear side of the rear wall of a pot —171— supported by the 35 furnace —2—, which will hereinafter be more fully explained.

40 The carriage —12— is moved longitudinally on the frame —1— to bring the gate —87— into and out of registration with the nozzle —89— by means of a piston —90— which is slidably mounted for longitudinal reciprocal movement in a suitable cylinder —91— and is connected with the carriage —12— by means of a piston rod —92— having one end thereof connected with the piston 45 —90— and extending forwardly therefrom with the forward end thereof screw threaded in a threaded aperture —93— provided in the rear end wall of the slide member —13—.

50 The piston rod —92— may be locked in position with the slide —13— by means of a lock nut —93— screw threaded on said rod. The cylinder —91— is supported in operative relation with the carriage —12— by a suitable bracket —94— which is secured to the rear end wall of the 55 main frame —1— by bolts or screws —95—.

60 The bracket —94—, in this instance, is provided with a vertically disposed wall —96— adapted to support one of the head members —97— for the cylinder —91—, while a second cylinder head —97'— is positioned at the rear end of the cylinder, the cylinder head —97—, the cylinder —91— and the cylinder head —97— being secured to the wall —96— of the bracket —94— by means of a plurality of, in this instance, four 65 tie rods —98— positioned at substantially each corner of a square and having one end thereof connected to the wall —96— with the other ends positioned in respective openings provided in the head —97— with nuts as —99— screw threaded on the outer ends of the rods to clamp the head —97—, cylinder —91— and head —97— to the wall —96—.

70 The piston —90—, in this instance, is of greater length than the longitudinal movement thereof 75 in any one direction and is provided with annular

recesses —100— and —101— in the rear and front end thereof respectively. The piston rod —92—, in this instance, is screw threaded in the front end of the piston —90— and extends part way therethrough with a screw as —102— positioned in the rear end of the piston and screw threaded in the rear end of the piston rod —92— for locking said rod to the piston, as clearly shown in Figure 7.

80 The lower wall of the cylinder —91— is provided with a pair of spaced ports —103— and —104— communicating with the interior of the cylinder at the rear and front end respectively of the piston —90— when the piston is in the extreme front or rear position. That is, when the piston —90— is in the rear position as illustrated more clearly in Figures 2 and 7, the port —104— is in communication with the interior of the cylinder —91— at the front end of the piston —90— and when the piston —90— is in the forward position, the port —103— is in communication with the interior of the cylinder at the rear of the piston.

85 The cylinder —91— is also provided with a second pair of ports —105— and —106—. The port —105— is positioned in the rear cylinder head —97— with one end thereof communicating with the interior of the cylinder —91— and the outer end connected with a conduit —110—, while the port —106— is positioned in the head —97— with one end communicating with the front end of the cylinder and the other end connected with a conduit —111—. The ports —103— and —105— are connected intermediate their ends by a passageway —107— and the ports —104— and —106— are connected intermediate their ends by a passageway —108—.

90 The passageways —107— and —108— have respective enlarged portions —107'— and —108'— intermediate the ends thereof adapted to receive a valve member —112— similar to the valve member —82— provided in the cylinder —66—, said valve members —112— being tubular in cross section with the inner ends thereof closed and tapered to correspond to a valve seat —113— formed at the junction of the inner end of the enlarged portion —107'— or —108'— and the remainder of the passageway —107— or —108— for preventing the flow of fluid from the port —105— to the port —103— or from the port —106— to the port —104—.

95 The inner ends of the valves —112— are also provided with a series of apertures —114— extending from the outer tapered face thereof to the interior of the valve, so that fluid entering the ports —103— or —104— may move the valves —112— outwardly away from the respective seats —113— and then enter the port —105— or —106— and respective end of the interior of the cylinder —91— through the apertures —114— of the 100 respective valve members —112—.

105 The piston —91— is retarded or cushioned in its longitudinal movement as it approaches the outer head —97— by means of a cylindrical member —115— secured in the head —97— by means of a screw —116— and which extends inwardly from the head a short distance, and adapted to register the recess —100— provided in the rear end of the piston —90— as said piston approaches the head —97—.

110 A relatively small passageway —115'— extending from the inner end of the member —115— inwardly and formed to communicate with the port —105— so that any liquid contained in the recess —100— upon the entrance of the member —115—

—115—, will slowly escape through the passage —116— and thereby cushion the rearward movement of the piston —90—.

The forward movement of the piston —91— is likewise retarded by means of a cylindrical member —117— adapted to fit in the recess —101— provided in the front end of the piston —90— and secured to the inner face of the head member —97—, said member —117— being provided with a relatively small passageway —118— in one side thereof for permitting the oil, which is trapped in the recess —101— as the member —117— enters therein, to slowly escape into the port —106—; the member —117—, head —97— and wall —96— each being provided with a suitable opening therethrough for receiving the piston rod —92— while a suitable aperture may be provided as shown in Figure 7 in the wall —96— and forward portion of the head —97— for receiving packing as —119— and a follower member —120— for preventing escapement of liquid along the piston rod —92—.

A suitable valve as —123— for controlling the liquid as oil under pressure, for actuating the pistons —90— and —65—, may be positioned in any suitable place and, in this instance, is mounted on a bracket —124— secured by bolts —125— to the rear vertical face of one of the leg members —8— for the frame —1—, as more clearly illustrated in Figures 1 and 2. The valve —123— is positioned in a plane below the cylinders —66— and —91— and, in this instance, consists of a substantially cylindrical body portion —125— having end plates —126— and —127— secured by bolts or screws —128— to either end thereof, said end plates having the lower portion thereof extended downwardly to form brackets —126— and —127— respectively adapted to be secured by bolts as —129— to the upper face of the bracket —124—.

An inlet chamber —130— is positioned in the lower portion of the body —125— and extends substantially the entire length thereof with the ends terminating in upwardly extending vertical chambered portions —131— and —132— positioned near the ends of the body —125—. The chambered portions —131— and —132— are each connected by respective ports —133— and —134— to respective control chambers —135— and —136— positioned in spaced relation intermediate the end chambers —131— and —132—, said control chambers —135— and —136— being connected with a common discharge chamber —137— located intermediate the control chambers and substantially midway between the ends of the body —125— by respective ports —138— and —139—.

The ports —133—, —134—, —138— and —139— are substantially circular in cross section and constructed with substantially the same diameter, and are arranged in the same plane longitudinally of the body —125— and adapted to receive therein a suitable piston as —140— which is slidably mounted for longitudinal reciprocative movement in said ports.

A piston rod as —141— is connected at one end with one end of the piston —140—, and extends outwardly through a suitable opening provided in one of the end plates as —127— of the valve and has secured to the outer end thereof a suitable bracket —142— adapted to be pivotally connected at —143— to a control lever —144— which, in this instance, is pivoted at —145— intermediate its ends to a bracket —146—

secured to the adjacent portion of the main frame —1— for actuating said piston.

The piston —140— in this instance, is provided with a reduced portion —147— intermediate the ends thereof for connecting one of the control chambers as —136— with the discharge chamber —137— when the piston is in one extreme position as illustrated in Figure 8, and also for connecting the control chamber —135— with the discharge chamber —137— when the piston is in the other position as illustrated by dotted lines in Figure 8. One end as —138— of the piston is also reduced in diameter to permit the port —133— to be opened without an excessive movement of the piston —140—.

The control chamber —136— is connected with one end of the pipe or conduit —110— which is connected with the port —105— provided in the head —97— of the cylinder —91—. The discharge chamber —135— is connected to one end of the pipe or conduit —111— which is connected with the port —106— provided in the head —97— so that any liquid entering the chamber —136— will be conducted by the pipe —110— to the outer or rear end of the interior of the cylinder —91— for moving the piston —90— forwardly, while any liquid entering the chamber —135— will be conducted to the inner or forward end of the cylinder —91— for moving the piston —90— in the opposite direction.

The inlet chamber —130— has connected thereto an inlet pipe —150— which may be connected to any suitable source for supplying liquid, under pressure, as a storage tank or pump, not shown. The discharge chamber —137— has connected therewith a discharge pipe as —151— which may be connected with the source of liquid supply for returning the liquid thereto.

It may now be clearly understood that when the piston —140— for the valve —123— is moved to the extreme inner position, as illustrated by dotted lines in Figure 8, that any liquid, as oil under pressure, entering the inlet chamber —130— through the inlet pipe —150—, will pass through the end chamber —132—, the port —134— to the control chamber —136—. Then as the port —139— will be closed by the piston —140—, the oil will pass out through the conduit —110— to the port —105— in the outer end —97— of the cylinder —91—. The valve —112— positioned in the passageway —107— will be closed by the action of the oil, which will act upon the piston —90— to move said piston forwardly in the cylinder —91—.

This forward movement of the piston —90— will move the die supporting carriage —12— forwardly to bring the gate —87— into casting relation with the discharge nozzle —89—. As the piston —90— approaches the limit of its forward movement, the port —103— in the cylinder —91— will be uncovered and the oil will then pass through said port and conduit —74— into the port —76— of the cylinder —66—, but as the piston —65— provided for said cylinder is in the rear position closing the inner end of said port as illustrated in Figures 2 and 8, the oil pressure will force the respective valve member —82— outwardly away from its seat —83— which opens the apertures —85— permitting the oil to pass through said apertures into the by-pass —78— and into the outer end of the inner chamber of the cylinder —66— thereby causing the piston —65— to move forwardly which will actuate the toggle link connection connecting the plate —15— with the movable die plate —38— by the rack —150—

—44— swinging the segmental gears —44— about their respective axes —46— which causes the die supporting plate —38— and the die carried thereby to be moved forwardly into casting 5 relation with the fixed die section —36— as the piston —90— reaches the end of its forward movement.

It is evident that any oil contained in the forward portion of the cylinder —91— at the beginning 10 of the forward stroke of the piston —90— will pass through the port —106—, conduit —111— into the control chamber —135— of the valve —123—; thence through the port —138— to the discharge chamber —137— and out through 15 the discharge pipe —151—. As the piston —65— is moved forwardly, the oil contained in the cylinder —66— will be forced out through the port —77—, conduit —75— to the port —104— in the cylinder —91—, but as the inner end of this 20 port is closed at this time by the piston —90—, the pressure of the oil contained in the port —104— will open the valve —112— which permits the oil to pass through the apertures —113— contained in this valve and out through the conduit —111—, chamber —135— port —138— and discharge chamber —137— to the discharge pipe —151—.

It is also now evident that by moving the piston —140— to an intermediate position to 30 close both ports —134— and —139— for preventing any back flow of the oil from the chamber —136—, the carriage —12— will be positively maintained in casting relation with the nozzle —89—, and that the die sections —36— and —37— will remain in casting relation with each other regardless of any pressure that may 35 be exerted on the carriage —12— or movable die section —37— during the casting operation due to the inelasticity or incompressibility of the oil.

When the valve piston —140— is moved to the outer position as illustrated by full lines in Figure 8, this will connect the control chamber —135— with the inlet chamber —130— and the control chamber —136— with the discharge chamber —137— which will permit the liquid to pass through the conduit —111— into the forward end of the cylinder —91— which will cause the piston —90— to move outwardly until the port —104— is uncovered, whereupon the liquid 50 will pass through said port and conduit —75— to the port —77— of the cylinder —66—.

The piston —65— contained in the cylinder —66— being in the forward position, the inner 55 end of the port —77— will be closed thereby which will cause the action of the oil to open the valve —82— and pass through the passageway —81— and by-pass —79— into the forward end of the cylinder —66— which will cause the piston —65— to be moved rearwardly to open the die sections as the piston —90— moves the die supporting carriage —12— rearwardly to bring the gate —87— out of casting engagement with the discharge nozzle —89—.

65 The oil contained in the outer end of the cylinder —66— will, of course, pass through the port —76— and conduit —74— through the passageway —107— opening the valve —112— and thence through the port —105—, conduit 70 —110— to the control chamber —136— where it reaches the discharge chamber —137— through the port —139— and thence back to the sources of supply through the pipe —151—. Thus it is seen that the die supporting carriage 75 —12— is first moved by the action of the piston

—90— to bring the discharge nozzle —89— into casting relation with the gate —87— provided on the fixed die supporting plate —14— and then the piston —65— is actuated to bring the die sections —37— and —36— into casting relation at which time the toggle link mechanism is brought to the locking position to securely maintain said die sections in casting relation and after the casting has been formed, the die supporting carriage is first moved rearwardly by the action of the piston —90— to bring the gate —87— and discharge nozzle —89— out of casting relation and then the piston —65— is actuated to move the die section —37— out of casting relation with the die section —36—.

It will be noted by referring to Figures 1 and 11 that the conduits —74— and —75— are each composed of a plurality of pipes connected by elbows and arranged at right angles to each other and having a plurality of, in this instance, three 95 swivel joints —155—, interposed therein for permitting the free relative longitudinal movements of the cylinders —91— and —66—.

The swivel joints —155— may be constructed in any suitable manner to permit the free relative 100 turning movements of the adjacent portions of the conduit with which they are connected and at the same time, prevent any leakage or escapement of the liquid passing therethrough.

The swivel joints —155—, in this instance, consist of a tubular body portion —156— screw threaded or otherwise secured in a liquid tight manner to one portion as —A— of the conduit to turn therewith, while the adjacent portion of the conduit as —B— positioned intermediate the 110 inner end of the portion —A— of the conduit and an inwardly extending annular flange —158— provided in the inner wall of the body —156— intermediate the ends thereof.

A suitable flange nut as —159— may be mounted 115 on the pipe —B— and screw threaded in the adjacent end of the body —156— for compressing a suitable packing member as —160— between the inner end of said nut and the flange —158— for preventing escapement of the liquid between 120 the portion —B— of the conduit and the body —156— of the swivel joint.

The delivery or melting pot —171— to which the delivery nozzle —89— is secured is a U or cup-shaped receptacle substantially circular in 125 cross section and provided with an outwardly extending annular flange —172— at its upper open end. The pot is positioned within the upper portion of the furnace —2— with the flange —172— resting upon the upper surface of a metal cover 130 plate —173— secured in any well-known manner to the upper end of the furnace —2—, said pot being secured in position by bolts or screws —174— passing through suitable openings provided in the flange and screw threaded in the cover plate 135 —173—.

The pot —171— may be further supported in its set position in the furnace against any lateral movement which might be caused by the die supporting carriage when coming into casting relation with the delivery nozzle —89— by a horizontally disposed stay rod —175— adjustably secured to the outer end of the furnace —2— and which extends within the furnace with the inner end thereof in contact with the rear wall of the pot as more clearly illustrated in Figure 1.

The interior of the pot —171— is formed with a substantially annular cylinder supporting boss —176— connected with and extending upwardly from the bottom of the pot, (see Figures 9 and 133

10), said boss —176— being supportably connected with the side wall of the pot by two pairs of diametrically opposed webs —177— and —178— positioned at right angles to each other.

5 The boss —176— is provided with a vertically disposed bore —179— therein which extends from the top of the boss downwardly to substantially the plane of the bottom of the pot and is connected with the delivery nozzle —89— by a duct

10 —180— provided in the spout —170— and connected with the lower end of the bore —179—.

A cylinder member —181— having its lower end somewhat reduced in diameter to fit the bore —179— is positioned in said bore and extends 15 some distance above the boss —176—. The cylinder —181— is provided with a vertically disposed bore or pressure chamber —182— therethrough adapted to receive a plunger —183— which is mounted for reciprocative longitudinal movement 20 in said bore.

The cylinder member —181— is secured in the boss —176— by a pair of clamps —184— which are positioned at opposite sides of the upper end of the cylinder —181— and the upper end of the webs —178— which are extended upwardly above the boss —176— to substantially the plane of the upper end of the cylinder member —181—, said clamps being secured in holding relation with the cylinder —181— by means of respective screws 30 —185— which pass through suitable openings provided in the clamps —184— and screw threaded in the upper end of respective webs —178—. The cylinder member —181— is also provided with a pair of diametrically opposed 35 inlet ports —186— in registration with the upper end of the boss —176— for permitting the molten metal contained within the pot —171— to pass into the cylinder bore —182— when the plunger —183— is in its up position when the lower end 40 of the plunger is in registration with or in a plane above said inlet ports.

The plunger —183— is moved longitudinally downward in the bore —182— for forcing the molten metal contained therein through the duct 45 —180— and delivery nozzle —89— into the dies by means of a piston —187— connected at the upper end of a piston rod —188— and mounted for longitudinal reciprocative movement in a vertically disposed cylinder —189— positioned in 50 a plane above the plunger cylinder —181—.

The cylinder —189— is supported in spaced relation with the pot —171— by means of a U-shaped bracket —190— having the lower end thereof provided with outwardly extending flanges —191— and secured by screws —174— to 55 the cover plate —173— of the furnace —2—.

The upper end —192— of the bracket —190— is constructed to form one of the heads for the cylinder —189— while a second head member 60 —193— is positioned at the upper end of the cylinder, said head —193— and the cylinder being secured together and to the bracket —190— by means of a plurality of, in this instance, four tie bolts —194— equally spaced at the corners of a 65 square and having their lower ends secured to the upper end of the bracket —190— and their upper ends passing through suitable openings in the cylinder head —193— and provided with nuts —195— screw threaded thereon for clamping said 70 head —193— and cylinder —189— to the bracket —190—.

The piston rod —188—, in this instance, extends downwardly through a suitable opening —197— in the head portion —192— of the 75 bracket —190— and is of such a length that

when the piston is in its extreme upper position, the outer end of the piston rod —188— will be positioned a short distance below the head —192—.

A suitable gland nut —198— and packing 80 —199— may be mounted on the rod —188— and secured in the head portion —192— for preventing leakage around the piston rod —188— during the reciprocative movement thereof.

A plunger rod —200— may be secured by a pin 85 as —201— or otherwise, to the plunger —183— and extends upwardly therefrom a distance equal to or greater than the longitudinal movement of said plunger. The adjacent ends of the piston rod —188— and the plunger rod —200— are each 90 provided with annular grooves —202— and —203— respectively, positioned a short distance from the ends thereof and adapted to receive the groove ends of a split connecting link —204— which is clamped together by screws —205—, the 95 link —204— being of sufficient length to position the lower face of the plunger —183— in registration with the inlet ports —186— of the bore —182— when the piston —187— is in its extreme up position, so that as the piston —187— is 100 moved downwardly, the plunger —183— will be likewise moved downwardly for discharging the molten metal contained in the bore —182—, and when it is desired to remove the plunger —183— from the bore —182— entirely, the link —204— 105 may be removed from the piston rod —188— and plunger rod —200— when the plunger —183— is in its up position. Then by moving the piston —183— downwardly, the piston rod —188— and plunger rod —200— may be connected by a similar but shorter connecting link, not shown, so that by the upward movement of the piston, the plunger —183— will be withdrawn from the bore —182—.

The piston —187— is designed to be hydraulically actuated in the cylinder —189— by any suitable liquid, as oil under pressure, and for this purpose, a port as —206— is provided in the head —193— having one end thereof in communication with the interior of the cylinder —189— and 120 the other end connected by a suitable pipe or conduit —207— to a suitable control valve —208—.

The other cylinder head —192— is likewise provided with a port —209— which has one end 125 thereof in communication with the lower end of the cylinder —189— and the other end connected by a suitable pipe or conduit —210— to the control valve —208—.

The control valve —208—, in this instance, is 130 positioned at the rear of the furnace —2— and secured by bolts or screws —211— to the upper face of a bracket —212— secured in any suitable manner as by screws —213— to the rear face of the furnace —2—, as more clearly shown in 135 Figure 1.

The control valve —208—, in this instance, for controlling the action of the piston —187— is similarly constructed to the control valve —123— for controlling the pistons —90— and —65— contained in the respective cylinders —91— and —66—; the control valve —208— being provided with a piston rod —215— connected at one end to a piston mounted for longitudinal movement in the valve —208— similar to the piston —140— 140 contained in the valve —123—, the outer end of the rod —215— being pivotally connected at —216— to a suitable operating lever —217— pivotally connected at —218— to a bracket —219— secured to the side wall of the furnace —2—. 145

The lever —217—, as shown in Figure 1, may extend rearwardly to the vicinity of the lever —144— for actuating the valve —123— so that the respective valves —123— and —208— may be conveniently operated without the operator changing his position.

The valve —208— is also provided with an inlet pipe —220— connected at one end with an inlet chamber similar to the inlet chamber —130— of the valve —123— and having the other end connected with any suitable source for supplying liquid under pressure, not shown.

An outlet pipe —221— is also connected with the valve —208— in communication with a discharge chamber similar to the discharge chamber —137— of the valve —123— for returning the liquid displaced by the action of the piston —187— to the source of supply.

It may now be clearly understood that when the die supporting carriage —12— has been moved forwardly to bring the discharge nozzle —89— into casting relation with the gate —87— and that with the die sections —37— and —36— in the closed position as indicated by dotted lines in Figure 1, it is only necessary for the operator to move the lever —217— and manipulate the valve —208— to admit oil through the conduit —207— and port —206— to the upper end of the cylinder —189— to cause the piston —187— and plunger —183— connected therewith to move downwardly and discharge the molten metal contained in the bore —182—, through the conduit —180— and discharge nozzle —89— into the cavity of the die sections —36— and —37—, after which the plunger —183— may be returned to its extreme up position by reversing the position of the piston contained in the valve —208— which admits the liquid through the conduit —210— and port —209— to the lower portion of the cylinder —189— and also permits the liquid contained in the upper portion of the cylinder displaced by the action of the piston —187— to be returned to the source of liquid supply similar to the manner hereinbefore described for the pistons —65— and —90—.

It is also evident that should it be discovered at any time during the downward movement of the plunger —183— for discharging the molten metal into the die, that the delivery nozzle —89— is not in proper registration with the gate —87— or that the die sections —37— and —36— were not in their proper casting relation, or if, for any other reason, it should be desired to discontinue the flow of the molten metal through the duct —80— and discharge nozzle —89—, that the operator may substantially instantaneously discontinue the flow of said molten metal by manipulating the valve —208— and thereby discontinue the pressure on the piston —187— which would be impossible to do if the plunger —183— were actuated pneumatically or if the molten metal was being discharged by any of the well-known pneumatically operated devices.

Although I have shown and particularly described the preferred embodiment of this invention, I do not wish to be limited to the exact details of the construction shown as various changes both in the form and the relation of the parts thereof may readily be made without departing from the spirit of this invention as set forth in the appended claims.

I claim:

1. In a die-casting machine having a pair of movable die sections, actuating means for said sections comprising a fixed cylinder, a piston mov-

able in said cylinder and operably connected with one of the die sections, a second cylinder having a piston movable therein operably connected with the remaining die section and means for applying oil to each end of the cylinders comprising an intermediate and an end port, means connecting the end ports of the first-mentioned cylinder with a source of oil under pressure for causing the piston therein to bring the respective die section into and out of casting relation with a delivery nozzle, and fluid-conveying means connecting corresponding intermediate ports of the cylinders for causing movement of the piston of the second-mentioned cylinder as the piston in the first-mentioned cylinder approaches the end of its stroke to bring the die section connected therewith into and out of casting relation with the other die section.

2. A die-casting machine as in claim 1 wherein corresponding intermediate and end ports are in communication with each other.

3. A die-casting machine as in claim 1 wherein corresponding intermediate and end ports are in communication with each other, and a valve associated with said ports adapted to permit the flow of oil through one of said ports in one direction only.

4. A die-casting machine as in claim 1 wherein corresponding intermediate and end ports are in communication with each other, and a valve associated with said ports adapted to permit the free passage of oil through both ports in one direction and a restricted amount of oil through one of the ports in the opposite direction.

5. A die-casting machine comprising a pair of movable die members, fluid pressure operating means adapted to move said die members in unison to and from a casting position, and a second fluid pressure operating means controlled by the action of the first-mentioned operating means at a predetermined position of the die members for automatically producing relative movement of said members.

6. In a die-casting machine having a pair of die sections movable into and out of casting relation with a delivery nozzle and with each other, a pair of fluid-operated actuating units for said die sections, each unit including a cylinder and a piston mounted therein, means operably connecting the units with the die sections, conveying means for supplying fluid under pressure to the cylinder in one of said units, and additional conveying means adapted to be opened and closed by the action of the latter unit for supplying fluid under pressure to the second unit whereby the operation of the second unit will be automatically controlled by the action of said latter unit.

7. In a die-casting machine having a pair of die sections movable into and out of casting relation with a delivery nozzle and with each other, a pair of fluid-operated actuating units for said die sections, each unit including a cylinder and a piston mounted therein, means operably connecting the units with the die sections, conveying means for supplying fluid under pressure to the cylinder in one of said units, and additional conveying means connecting the latter cylinder intermediate the path of movement of the corresponding piston with the end portions of the cylinder in the other operating unit for supplying fluid to the second-mentioned cylinder whereby the operation of the second-mentioned actuating unit will be automatically controlled by the operation of the first-mentioned actuating unit.

WILLIAM J. DURING. 150
